Primary Examiner—Prabhakar Deshmukh*Assistant Examiner*—Keli L Hill(74) *Attorney, Agent, or Firm*—Oliff & Berridge, PLC(57) **CLAIM**

The ornamental design for a packaging bottle, as shown and described.

DESCRIPTION

FIG. 1 is a front view of the packaging bottle;

FIG. 2 is a top view thereof;

FIG. 3 is a rear view thereof;

FIG. 4 is a bottom view thereof;

FIG. 5 is a left-side view thereof;

FIG. 6 is a right-side view thereof;

FIG. 7 is a planar cross-sectional view thereof taken along line 7—7 of FIG. 2;

FIG. 8 is a planar cross-sectional view thereof taken along line 8—8 of FIG. 2;

FIG. 9 is a planar cross-sectional view thereof taken along line 9—9 of FIG. 1;

FIG. 10 is a planar cross-sectional view thereof taken along line 10—10 of FIG. 1; and,

FIG. 11 is a planar cross-sectional view thereof taken along line 11—11 of FIG. 1.

The broken lines depict environmental subject matter only and form no part of the claimed design.

The thickness illustrated in the cross-sectional views forms no part of the claimed design.

A planar cross-section is one taken at a single instant geometric plane.
